EDWARD POWELL, OF PORTLAND, AND MILTON E. WILSON, OF MARSHFIELD, OREGON

BRUSH

Application filed October 13, 1930. Serial No. 488,392.

Our invention relates to brushes and more particularly to brushes where liquid soap, medicated fluids, polishes and other materials are to be carried within, the brush structure and are to be released therefrom, periodical-
 5 ly, or as desired by the user of the brush. A fountain being maintained within the body portion of the brush in which the fluids to be dispensed are normally carried. A plurality
 10 of exuding ports are disposed within the bristle carrying base with a slide valve disposed thereabove and which is normally maintained closed by spring action. A removable cap and plug, is disposed within the
 15 top of the brush, for filling and for other purposes. The bristle carrying portion of the brush disposed within the brush structure has a plurality of bristle carrying holes disposed in spaced relationship therethrough,
 20 into each of which thimbles may be pressed, into place and position, with the bristles of the brush being placed within the thimbles. The brush may be made of any desired shape, to adapt the same for the purpose intended.

25 The object of our invention is to provide a brush structure adapted for carrying fluids within a reservoir disposed therein which may be disposed by the hand manipulation of the valve that normally maintains the dis-
 30 charge ports in closed, liquid tight condition.

A further object of our invention consists in the forming of a fountain brush comprised of valved ports and one that may be used over relatively long periods of use with freedom
 35 from operating annoyances.

A further object of our invention consists in so constructing our brush that the desired amount of fluid may be dispensed therefrom at desired times and while the brush, is actu-
 40 ally in use.

A still further object of our invention consists in so constructing the bristle elements that each bristle may be removed and be re-
 45 placed with a minimum of effort and with a minimum of delay.

A still further object of our invention consists in so constructing a brush that the same may be used by physicians, artisans and
 50 others in the dispensing of desired elements

therefrom and while the brush is actually in use.

With these and incidental objects in view, the invention consists in certain novel features of construction and combination of parts, the essential elements of which are set forth in the appended claim, and a preferred form of embodiment of which is hereinafter shown with references to the drawings which accompany and form a part of this specification.

In the drawings:

Fig. 1 is a perspective, end view, of the assembled device.

Fig. 2 is a longitudinal, sectional, side view of the assembled device, the same being taken on line 2—2 of Fig. 1, looking in the direction indicated.

Fig. 3 is a sectional, top, plan view, of the assembled device, the same being taken on line 3—3 of Fig. 2, looking in the direction indicated.

Fig. 4 is a fragmentary, top, plan view partially in section, of the assembled device. In this view the top and central portion of the body of the brush is shown broken away to show the discharge ports and the valve for maintaining the same in closed position; in this view the discharge ports are shown open.

Fig. 5 is a sectional, end view, of the assembled device, the same being taken on line 5—5 of Fig. 2, looking in the direction indicated.

Fig. 6 is a side elevation, of a portion of the bristle holding structure and illustrating the thimble for holding the bristles in place within the bristle holding recess.

Fig. 7 is a sectional, side view of the thimble and illustrating the pin for maintaining the bristles in position within the thimble.

Fig. 8 is a side view illustrating the brush assembly having a closure plate 4, or cover, removably secured thereto to protect the bristles when not in use and to adapt the same for being carried in the pocket, or bag, or otherwise.

Like reference characters refer to like parts throughout the several views.

We preferably form our device of a body element 1, having a uniformly curved top

surface and having downwardly extending side walls 2 and end walls 3. A filler cap 4 is removably secured to the top wall. A bristle carrying bottom 5 is adapted for being pressed into place within the downwardly extending wall members and the same being made to a precision fit to form a liquid holding reservoir 6 within the body of the brush structure. Thimble holding recesses are formed within the base 5 by having sockets 7 downwardly extending from the base 5 and spaced apart. A thimble 8 is placeable within each of the sockets thus formed, the same also being made of precision dimension in order to hold the liquid within the body element and to form a liquid tight joint between the thimbles and the recess walls. The bristles to be placed within the thimble are placed therein as shown in Fig. 7 wherein the loop that is formed of the bristle and a pin 10 that is supported within the thimble walls is passed between the bristles to thereby maintain the bristle assembly lockably disposed within the thimble structure. A plurality of discharge ports 11 are disposed within and through the base 5, and a valve 12 is slidably disposed upon the inner surface of the base 5. The valve is maintained in a tight working relationship with the inner surface of the base 5 by any suitable reacting element, as through the use of a spring 13, one end of the spring 13 rests directly upon the upper surface of the valve and the oppositely disposed end of the spring is secured to one of the walls of the body element 1, as through the use of a screw 14. The screw 14 being threadably secured to one of the walls of the body element 1.

An actuating stem 15 is secured upon its one end to the valve and the oppositely disposed end of the valve extends through the wall of the body element, and a head 16 is disposed upon the oppositely disposed end of the stem and to that end that is disposed upon the outside of the body element 1, to facilitate its being manually manipulated. A reacting element, as a coil spring 17, normally maintains the valve closed and the head 16 distended, to thereby not only maintain the valve positioned above the discharge ports, but to maintain the head 16 distended and therefore adapted for manual manipulation.

A shoe is formed central of, and longitudinal of the valve 12 and that end of the reacting element 13 that engages thereupon is made to a shape and configuration to engage thereupon to thereby maintain the valve in position and alignment. A fastening chain 19 is secured to the under side of the closure 4 and to a boss 20 disposed within the body element. The object being to maintain the closure 4 fixedly positioned relative to the body element 1 and prevent loss or displacement. A ring 21 is disposed relative to the

head 16 to facilitate the hanging up of the brush when not in use.

When it is desired to dispense fluids from the reservoir 6, the valve is open for a sufficient amount of time to permit the fluid to flow through the discharge ports 11, but when a sufficient amount of fluid has been dispensed the stem is released and the reacting element 17 maintains the valve closed relative to the ports 11.

In Fig. 8 we have shown a closure that is adapted for engaging the downward extending walls of the body element and for attaching itself thereto. The purpose and object of the cover, is to protect the bristles of the brush when the same is being carried in the pocket or bag or otherwise of the user.

In our new and improved construction, as illustrated in the drawings we have illustrated the body of the brush structure, as having parallel side and end walls, but we do not wish to be limited to a structure of any particular shape, as the same may be made circular in horizontal cross sectional area, or of any other shape, to meet the trade requirements and the device may be made with equal facility as that of the construction herein shown and illustrated.

While the form of mechanism herein shown and described is admirably adapted to fulfill the objects primarily stated, it is to be understood that it is not intended to confine the invention to the one form of embodiment herein shown and described, as it is susceptible of embodiment in various forms, all coming within the scope of the claim which follows.

What we claim is:

A fountain brush comprising a hollow body element forming a reservoir and having a plurality of outlet ports disposed through its bottom, a valve slidably disposed within the reservoir, a stem extending outwardly from the valve, and through one of the side walls of the reservoir, a coil spring attached to one side wall of the reservoir and to the valve adapted to normally maintain the valve over the outlet ports, a laterally extending spring secured to another side of the reservoir and frictionally engaging the upper surface of the valve adapted to maintain the valve in tight working relation with the reservoir bottom, and a plurality of bristles secured to the underside of the reservoir bottom.

EDWARD POWELL.

MILTON E. WILSON.
